UNITED STATES PATENT OFFICE.

BRONSON CUSHING SKINNER, OF DUNEDIN, FLORIDA, ASSIGNOR TO SKINNER MACHINERY CO., OF DUNEDIN, FLORIDA, A CORPORATION.

HEATER.

1,321,678.

Specification of Letters Patent.

Patented Nov. 11, 1919.

Application filed March 27, 1919. Serial No. 285,405.

To all whom it may concern:

Be it known that I, BRONSON CUSHING SKINNER, a citizen of the United States, and a resident of Dunedin, in the county of Pinellas and State of Florida, have invented a new and Improved Heater, of which the following is a full, clear, and exact description.

The object of the invention is to provide a new and improved heater more especially designed for use in groves growing citrus fruit and in like open places, and arranged to insure lateral radiation of a large amount of heat from a point close to the ground. Another object is to permit of burning coke as a fuel to insure a red heating of the entire metallic shell. Another object is to permit of readily shipping or storing the heater in a knock-down condition and to allow of quickly assembling the parts without the use of skilled labor.

With these and other objects in view, the invention consists of certain novel features of construction as hereinafter shown and described and then specifically pointed out in the claim.

A practical embodiment of the invention is represented in the accompanying drawings forming a part of this specification in which similar characters of reference indicate corresponding parts in both views.

Figure 1 is a perspective view of the heater; and

Fig. 2 is a similar view of the body of the heater with the parts disassembled.

Fig. 3 is a similar view of the cover for the heater.

Fig. 4 is a like view of the carrying bail,

Fig. 5 is a perspective view of the grate, and

Fig. 6 is a similar view of one of the fastening bolts for the body of the heater.

The grate 10 of the heater is provided with a rim 11 from which depend legs 12 for supporting the grate a short distance above the ground. The shell 15 of the heater is made from a single piece of sheet metal bent to fit with its lower end exteriorly onto the rim 11, and the said lower end of the shell 15 is provided with spaced apertures 16 engaging lugs 17 projecting outwardly and integrally from the rim 11. The shell 15 when bent into place on the

rim 11 provides two overlapping side edges 18 and 19 having registering apertures 20 and 21 adapted to be engaged by bolts 22 for fastening the overlapping ends of the shell 15 together thus locking the lower end of the shell 15 in position on the rim 11 and its lugs 17. The shell 15 is provided a short distance above its lower end with a firing opening 25 for igniting the kindling wood held in the lower end of the shell on top of the grate 10. It is understood that coke is placed on top of the kindling wood and this coke is ignited from the burning kindling wood. By supporting the grate 10 above the ground the necessary amount of air for combustion readily passes through the grate to the kindling wood and to the coke to insure proper combustion of the fuel. It will be noticed that by the arrangement described the fire is located low down in the shell 15 and hence the latter is brought to a red heat throughout the length thereof and consequently a large amount of heat is radiated from the shell in a lateral direction.

After the coke is burning a suitable cover 30 may be placed on top of the shell 15. A bail 40 is preferably attached to the upper end of the shell to permit of conveniently carrying the heater in the grove or from one place to another.

The heater is preferably shipped and stored when in a knock-down condition as illustrated in Fig. 2, and the parts of the heater can be readily assembled whenever it is desired to use the heater.

Having thus described my invention, I claim as new and desire to secure by Letters Patent:—

A heater, comprising a grate provided with legs to support the grate above ground, the grate having a rim and lugs projecting radially from the rim, a shell made of a single piece of sheet metal bent to fit with its lower end received around said rim, said lower end of the shell being provided with holes registering with and engaging the said lugs to support the said shell, the shell having overlapping sides and having a firing opening a short distance above the grate, and fastening members removably fastening the overlapping sides together.

BRONSON CUSHING SKINNER.
